UNITED STATES PATENT OFFICE.

WILLIAM L. WATERS, OF MILWAUKEE, WISCONSIN.

COMMUTATOR.

No. 823,568.

Specification of Letters Patent.

Patented June 19, 1906.

Application filed December 5, 1904. Serial No. 235,462.

To all whom it may concern:

Be it known that I, WILLIAM L. WATERS, a subject of the King of England, residing at Milwaukee, in the county of Milwaukee and 5 State of Wisconsin, have invented a certain new and useful Improvement in Commutators, of which the following is a full, clear, concise, and exact description, reference being had to the accompanying drawings, forming 10 a part of this specification.

My invention relates to commutators, and particularly to commutators with which a plurality of brushes are employed; and the object of my invention is improved construction 15 of the commutator and its arrangement with respect to the armature.

To accommodate a great number of brushes, the commutator must offer considerable surface; but if the commutator is integral it becomes 20 very unsatisfactory on account of the heating which results, it being impossible to provide satisfactory ventilation to keep the segments cool. My invention, therefore, provides for a divided commutator or, in fact, 25 two commutators which may be of exactly similar construction and one disposed at either side of the armature. The segments of one of the commutators only is connected in the usual manner with the armature-coils, 30 while corresponding segments of both commutators are connected together by leads which may pass through the interior of the armature or through the axial ventilating-spacings ordinarily employed. Each commutator 35 is well provided with ventilating-openings, and the currents generated by the armature upon rotation pass outwardly through the commutator-ventilating channels and also cross the surface of the commutator-bars, and thus the commutator is kept 40 cool. I also provide a very simple and efficient arrangement of the commutators with respect to the armature, the armature and commutators being all mounted on a common sleeve which is keyed to the armature-shaft.

My invention will be best understood with reference to the accompanying drawings, in which—

50 Figure 1 is an end view of the armature and commutators, and Fig. 2 is a longitudinal sectional view taken on line 22 of Fig. 1.

Each commutator part consists of a supporting-frame in the shape of a pulley 1, 55 whose rim 2 and hub 3 are connected by spokes 4. A clamping-ring 5 engages each

side of the pulley, being provided with an annular groove 6 for engaging the edge of the pulley. The clamping-rings are provided with openings 7, through which bolts 8 pass 60 for clamping the rings against the pulley and for clamping the commutator-segments 9 about the periphery of the pulley. The armature 10 consists of end plates 11, between which are clamped the armature-laminations 65 12 by means of clamping-bolts 13. A sleeve 14 is secured to the shaft 15 by a key 16 and is provided with shoulders 17 and shoulders 18. The end plates of the armature are clamped to the shoulder 17, while the hubs 3 70 of the commutators are clamped against the shoulders 18, and thus the armature and commutators are rigidly connected together. The armature end plates may consist of a hub and spokes, or, as shown, these end 75 plates may be provided with ventilating-openings 19, which lead into the chamber 20 between the end plates and laminations. The armature-coils 21 may be arranged in any manner in the armature-teeth and their 80 terminals 22 connected with appropriate segments of one of the commutators. The corresponding segments of the commutators are connected by means of conductors 23, which pass through the ventilating-openings 85 19, and thus sufficient surface may be provided for the brushes 24, which may be of any number.

As the armature and commutators are rotated sufficient air-currents will be generated and will be forced through the ventilating-openings of the armature and through the channels 25 between the spokes and rings of the commutators and also over the surface of the commutator-segments to keep 90 the commutators and armature well cooled. 95

I do not wish to be limited to the exact construction and arrangement herein shown and described, as changes may readily be made without departing from the spirit of invention; but

I claim as new and desire to secure by Letters Patent—

1. The combination with an armature, of a commutator arranged at each side thereof and adapted to rotate therewith, the segments of one commutator being suitably connected with the coils of the armature, the segments of the other commutator having no direct connection with the coils, ventilating-passages through the interior of the armature, and conductors passing through said 105 110

- ventilating-passages and connecting with the segments of the commutators for affording an electrical path between the corresponding segments of the commutators.
5. 2. The combination with an armature, of a commutator arranged at each side thereof, said commutators being of similar construction, a supporting-rim for each commutator for supporting the segments thereof, clamping-rings engaging the edges of said rim and said segments, a hub for each commutator, spokes connecting said rim with said hub to form passage-ways through each commutator, the segments of one commutator being 10 suitably connected with the coils of the armature, the segments of the other commutator having no direct connection with the coils, ventilating passage-ways through the core of the armature, and conductors passing 15 through said passage-ways and connecting corresponding segments of the commutators.
3. The combination with an armature, of a commutator associated with each end thereof, a sleeve provided with two sets of shoulders, the end plates of said armature engaging said sleeve against one set of shoulders, said commutators being mounted on said sleeve, and each engaging one of the other shoulders, the segments of one commutator 20 being suitably connected with the coils of the armature, and conductors for joining corresponding segments of the commutators.
4. The combination with an armature, of two commutators, one disposed at each side 25 thereof, a sleeve, sets of shoulders on said sleeve, the end plates for said armature engaging said sleeve and one set of said shoulders, commutators being mounted on said sleeve, and each engaging one of the other shoulders, ventilating passage-ways extending 30 through said armature and through said commutators, the segments of said commutators being suitably connected with each other and with the armature-coils.
45. 5. The combination with an armature, of a commutator disposed at each end thereof, a sleeve provided with two sets of shoulders, the end plates of said armature engaging said sleeve and one set of shoulders, said commutators being also mounted on said sleeve and each engaging one of the other shoulders, ven- 40 tilating passage-ways extending through said armature and through said commutators, the segments of one commutator being suitably connected with the coils of the armature, 55 the segments of the other commutator having no direct connection with the coils, and conductors passing through the ventilating passage-ways of the armature for connecting corresponding segments of the commutators. 6c
6. The combination with an armature, of a commutator disposed at each side thereof, a sleeve upon which said armature and said commutators are rigidly mounted, a supporting-rim for the segments of each commutator, 65 clamping-rings for securing the segments of each commutator to the corresponding supporting-rim, a hub for each commutator, spokes extending from the rim to the hub to form ventilating passage-ways, ventilating 70 passage-ways through the armature, conductors passing through said armature passage-ways for suitably connecting together corresponding commutator-segments, the segments of one of said commutators being suitably 75 connected with the armature-coils.
7. The combination with an armature, of a commutator disposed at each side thereof, a sleeve provided with two sets of shoulders, the end plates of the armature engaging said 80 sleeve and one set of shoulders, hub portions of the commutators mounted on said sleeve and engaging the other shoulders, a supporting-rim for each commutator, spokes for connecting each supporting-rim with the corre- 85 sponding hub, clamping-rings for securing the commutator-segments to the rim, said clamping-rings and spokes forming passage-ways through the commutators, ventilating pas- 90 sage-ways through the armature, and conductors passing through said armature pas- sage-ways for connecting together correspond- 95 ing segments of the commutators, the segments of one of said commutators being suitably connected with the armature-coils. 95

In witness whereof I hereunto subscribe my name this 1st day of December, A. D. 1904.

WILLIAM L. WATERS.
